CLAIM

The ornamental design for a package having surface ornamentation, as shown and described.

DESCRIPTION

FIG. 1 is a perspective view of a package having surface ornamentation embodying our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures depict environmental subject matter only and form no part of the claimed design.

The stippling in the figures indicates color, but not a particular color.
